UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

1,353,834.

Specification of Letters Patent. Patented Jan. 15, 1918.

Application filed December 8, 1916. Serial No. 135,834.

To all whom it may concern:

Be it known that I, OSCAR JUNGGREN, a citizen of the United States, residing at Schenectady, county of Schenectady, State of New York, have invented certain new and useful Improvements in Elastic-Fluid Turbines, of which the following is a specification.

The present invention relates to elastic fluid turbines of the axial flow type, and particularly to an improved arrangement for staying or bracing the buckets of such turbines.

In the later stages of such turbines it is necessary to employ long buckets in order to obtain proper passage for the elastic fluid, the volume of which becomes very large. For example, in some instances the buckets may be 30 inches or more in length.

With such long buckets there is a tendency for the buckets to bend under load in the direction of rotation, which bending is serious as it tends to produce a bending action on the bucket covers which may eventually cause them to break. Difficulty is also experienced with long buckets due to their vibrating.

The object of the present invention is to provide an improved arrangement for staying or bracing the buckets between their ends which will overcome the above referred to difficulties.

According to my invention I provide diagonally extending stays, as wires or rods, each of which extends across the edges of a group of buckets. These stays may be on only one side or on both sides as found desirable, and they are fastened in notches or recesses in the edges of the buckets, as, for example, by welding, brazing, or soldering. Each stay is so arranged that it extends entirely across its own group of buckets and overlaps on to the group on each side. In other words, the ends of the stays overlap each other. This ties the respective groups together. The bucket cover is made in sections, as is well known, and the stays are preferably so arranged that the breaks in the bucket cover occur at points about midway between the ends of the stays. The function of these braces or stays is to take up the torque and thereby prevent each group of buckets from moving. At the same time they prevent vibrations of the

individual buckets, and also since they overlap they prevent any group vibration.

In the drawing, Figure 1 is a view in side elevation of a portion of a turbine wheel with my improved stays applied thereto, and Fig. 2 is a section taken on line 2-2, Fig. 1.

Referring to the drawing, 5 indicates a turbine wheel to the periphery of which are attached the turbine buckets 6. The buckets may be attached to the wheel rim in any suitable manner, as for example, by the dove-tail arrangement indicated at 7 in Fig. 2. 8 indicates the bucket cover which is formed in sections and is riveted to the bucket ends by means of tenons formed integral with the buckets, as is well known. 9 indicates the stays which extend diagonally across the buckets, the same being set into notches 10 in the bucket edges, as indicated in Fig. 2. These stays divide the buckets into groups, and in the present instance, a stay is shown on each side of each group. The direction of rotation of the turbine wheel is indicated by the arrow in Fig. 1 and the stays preferably extend diagonally from the wheel rim toward the bucket cover in the direction of rotation so that such stays are put under tension in holding the bucket groups from moving.

As will be seen from Fig. 1, the stays overlap at their ends by an amount sufficient to effectually tie the groups of buckets together. This prevents any group vibration. It will also be noted that the breaks between the bucket cover sections, as indicated at 11, occur about midway of a stay and preferably, as shown, each stay extends from about the center of one bucket cover section to about the center of the next. This ties the buckets connected to one cover section to the buckets connected to the cover section on each side thereof, thus preventing vibrations of the group of buckets connected with any cover section.

The above described arrangement has the advantage that it is cheap and simple to install and that it performs a double function in that it both prevents the groups of buckets from moving under load in the direction of rotation, and prevents the individual buckets or any groups thereof from vibrating.

In accordance with the provisions of the patent statutes, I have described the prin-

5 principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

- 10 1. In an axial flow turbine, the combination of a shaft, a rotor thereon located in a plane at right angles to the shaft and having radially extending buckets thereon, a cover for the buckets, and diagonally extending stays 15 extending across the edges of the buckets and fastened thereto, said stays dividing the buckets into groups and serving to prevent the groups from moving in the direction of rotation when under load, 20 and also to prevent vibrations of the buckets.
2. In an axial flow turbine, the combination with a rotor having buckets thereon and provided with a bucket cover divided 25 into sections, of diagonally extending stays extending across the edges of the buckets

and fastened thereto, said stays dividing the buckets into groups and at least some of them extending from a point beneath one cover section to a point beneath the 30 next one.

3. In an axial flow turbine, the combination with a rotor having buckets thereon and provided with a bucket cover divided into sections, of diagonally extending stays 35 extending across the edges of the buckets and fastened thereto, said stays overlapping each other at their ends and at least some of them extending from a point beneath one cover section to a point beneath the next one. 40

4. In an axial flow turbine, the combination with a rotor having buckets thereon and provided with a bucket cover divided into sections, of diagonally extending stays 45 extending across the edges of the buckets and fastened thereto, each stay extending from a point beneath one bucket cover section to a point beneath the next, said stays overlapping each other at their ends.

In witness whereof, I have hereunto set 50 my hand this 7th day of December 1916.

OSCAR JUNGGREN.
